BUFFING DEVICE

Paul E. Hawkinson, Minneapolis, Minn., assignor
to Paul E. Hawkinson Company, Minneapolis,
Minn., a corporation of Minnesota

Application December 4, 1939, Serial No. 307,477

3 Claims. (Cl. 29—78)

My present invention relates to buffer devices and is particularly directed to an improved buffer wheel or head. The improved buffer head is adapted for various different kinds of work but has been especially designed to meet the requirements of a buffer wheel for use in the buffing of tire casings in the preparation thereof for retreading.

For this particular purpose, it has been the old and common practice to use a buffer wheel provided with permanently applied barbs or teeth. These teeth wear away quite rapidly and with this old arrangement new complete heads were frequently required.

My invention involves a novel buffer wheel and a readily replaceable buffer strip. The coarseness and rapidity of the buffing action will depend on the nature of the barbs or cutting particles on the buffer strip and these, of course, may be varied. When the buffer strip is provided with coarse barbs or teeth, the buffing action will resemble that of a rasping action, but the buffer strips employed may be provided with teeth or barbs of varying coarseness or cutting action according to the kind of work.

From the foregoing it will be understood that the term "buffing" is herein used in a broad and liberal sense.

The invention is directed particularly to the novel features as to construction which make the use of the inexpensive buffer strips an easy operation quickly performed.

A commercial form of the invention is illustrated in the accompanying drawings wherein like characters indicate like parts throughout the several views.

Referring to the drawings:

Fig. 1 is a perspective showing the improved buffer wheel and band applied to the rotor of an electric motor and showing also an associated housing or shield and a transparent guard window, which latter features constitute no part of the present invention;

Fig. 2 is a fragmentary section taken on the line 2—2 of Fig. 1;

Fig. 3 is a fragmentary view partly in side elevation and partly in section showing sections of a split or two-part buffer wheel and the ends of the buffer band;

Fig. 4 is a perspective showing the buffer wheel and band opened up and illustrating the manner of applying the band thereto;

Fig. 5 is a perspective showing the opened or spread buffer wheel and band and levers for bringing the same to closed or operative positions;

Fig. 6 is a view in perspective showing a hub collar which constitutes an important part of the buffer wheel;

Fig. 7 is a view corresponding somewhat to Fig. 5 but showing the sections of the buffer wheel closed in position to receive the hub collar which is applied thereto;

Fig. 8 is an end elevation showing several of the normally straight buffer strips or bands placed in nested condition for shipment or storage.

In Fig. 1 the numeral 10 indicates an electric motor and the numeral 11 the rotor shaft or spindle on which the buffer wheel, presently to be described, is detachably secured. The numeral 12 indicates the housing or guard associated with the wheel and in practice usually connected to the source of suction or partial vacuum. The numeral 13 indicates the transparent window or shield through which the operator observes the work being performed by the buffing wheel. As before indicated, the elements 12 and 13 constitute no part of the present invention.

The buffer wheel, in accordance with my invention, is made of two sections 14 and 15 that split the complete wheel diametrically. These sections 14 and 15 have interlapping hinge lugs 16 pivotally connected by the hinge pin 17 or otherwise. The said sections 14 and 15 at the axis of the wheel are provided with split hub sections 14' and 15' which, when forced together, make a complete hub. The sections 14 and 15 at one side have semi-disc-like webs that are provided with semi-cylindrical rim sections 14a and 15a respectively, and at their ends they are provided with inturned flanges or lugs 14b and 15b that are tapped out to receive screws 18. When the sections of the buffer wheel are forced together, as shown in Fig. 7, they are interlocked by a collar 19 that can be freely telescoped over the same.

By reference particularly to Fig. 3 it will be noted that the band 20, at its ends, has curved portions that unite with the anchoring ends 20' and that the flanges and semi-cylindrical rim sections 14a and 15a are joined to their respective lugs 14b and 15b by curved or truncated surfaces, the radii of which are much greater than the radii of the curved end portions of the said band 20. This arrangement, as clearly shown in said view, Fig. 3, normally spaces the curved portions of the band from the curved portion of the ends of the segmental sections. This is highly important for reasons above indicated, but which

may be further explained as follows. When the segments or semi-cylindrical sections are forced together and the buffer band is tightly drawn onto the same, the curved end portions of the said band, under increasing tension, will tend to straighten or become more nearly straight and will produce increasing resistance as the sections are closed. The arrangement should be such that the curved end portions of the band will not be brought completely into contact with the curved end portions of the segments. By such an arrangement the band will never be axially stretched and certainly not to a breaking point because the tension will always be taken up in the curved end portions of the band when the segments are closed to the limit.

The buffer band or element may take different forms but as a feature of the invention are steel strips or bands 20 that are normally straight but capable of being readily bent into circular form. The barbs on this band are preferably made by the use of a more or less dull punch or punches that produce ragged or sharp barbs or teeth 21 that have a rapid cutting action. This buffering strip has end flanges 20' that are abruptly bent inward closely approaching right angles to the bodies thereof; while the lugs 14b and 15b are rounded for an important purpose which will hereinafter appear. The barbs 21 are preferably arranged in oblique cross rows to give a continuous or unbroken cutting action under rotation of the wheel.

The inturned ends or flanges 20' are perforated so that the screws 18 may be freely passed therethrough and screwed into the holes in the lugs 14b and 15b. In practice the buffer strips may vary slightly in length and in the angle in which the ends are turned inward; but in spite of this fact, it is highly important that the buffer strip, when applied to the closed buffer wheel, will be drawn very taut but will not be broken. This is accomplished largely by the fact that after the buffer strip is applied to the wheel sections and the wheel sections are being moved together, there will be clearance between the angles at the ends of the strip and the rounded portions of the lugs 14b and 15b so that in closing the wheel sections under high pressure the straightening of the steel or metal band at its angular ends will compensate for some inaccuracies in the making of the buffer strips. Obviously when the screws 18 are inserted through the ends of the buffer strip and screwed into the lugs, the buffer strip will be very securely anchored to the sections of the buffer wheel. Here it may be noted that the long unthreaded ends of the screws 18 assist in effecting the proper entrance of the screws and this is important especially where the alignment of the holes in the lugs and the ends of the strip is not perfect.

Obviously considerable force will be required to close the sections of the wheel with the buffering strip or band applied thereto as shown in the drawings; and, hence, I provide levers 22 provided with pins 23 that are engageable in holes 24 in the webs of the wheel sections. When the levers are used like a pair of tongs, the wheel sections can be closed and the buffering strip tightly stretched thereon and the collar 19 then telescoped over the split or segmental hub-forming sections 14' and 15'.

When the buffer wheel and band are applied,

as shown in Fig. 7, the entire wheel may then be slipped on to the shouldered or reduced end of the motor shaft or spindle 11 and there clamped by a nut 25, or the like, so that the wheel will be revolved with the rotor of the motor. Preferably a washer 26 is applied between the nut 25 and the hub portion of the buffer wheel so that the latter will keep the collar 19 pressed on to the hub sections. In Fig. 4 the numeral 27 shows a screwdriver used to tighten the screws 18.

The fact that the buffer strips are normally straight is important for the main reason that they may be closely packed in packages of proper shape for storage or shipment. Fig. 8 illustrates the manner of nesting the normally straight strips but in practice by giving the proper inclination to the ends 20' of the strips 20, they may be nested in complete contact.

In actual practice this improved buffer wheel structure has been found highly efficient. Buffer strips of any desired coarseness or fineness may be produced at small cost and by the successive use thereof on the common wheel, the total cost of buffering operations has been very greatly reduced.

Another advantage in the split buffering head described, is the fact that after the collar 19 is once applied to a shaft, the device may be applied or removed radially of the shaft, which is particularly important in that it permits the split head to be readily applied to or removed from the intermediate portion of a shaft between other shaft carried devices without removing such other devices.

A preferred commercial form of the invention has been shown in the drawings and described, but it will be understood that various alterations in the details of construction and arrangement of parts may be made within the scope of the invention herein disclosed and claimed.

What I claim is:

1. A buffer wheel made up of hingedly connected segments, each segment having an approximately semi-cylindrical rim flange terminating in radially inturned anchoring lugs, and a buffer band applied around the rim flanges of said segments and having inturned ends anchored to the respective lugs, the ends of said buffer band being joined to their inturned ends by curved portions, and said rim flanges being joined to their respective anchoring lugs by curved or truncated portions, the radii of the arcs of which latter are much greater than the radii of the arcs of the curved ends of said buffer band, whereby, under forced closing of said segments, the curved portions of said band will be drawn into shapes more closely corresponding to the curve of the truncated portions of said rim flanges.

2. The structure defined in claim 1 in which said segments are provided with means for the detachable connection of levers thereto.

3. The structure defined in claim 1 in which said segments are provided at the axis of the buffer wheel with hub segments, and in further combination with a collar applicable over said hub segments and operative when applied to hold the segments closed with the buffer band under sufficient tension to hold said buffer band with its curved end portions under straightening tension.

PAUL E. HAWKINSON.
